UNITED STATES PATENT OFFICE

CHARLES E. LUCKE, OF NEW YORK, N. Y., ASSIGNOR TO THE BABCOCK & WILCOX COMPANY, OF BAYONNE, NEW JERSEY, A CORPORATION OF NEW JERSEY

WASTE HEAT BOILER

Application filed October 10, 1928. Serial No. 311,428.

One of the objects of my invention is the provision of means introduced in the path of the flow of the gases from the internal combustion engine to the steam boiler for converting a pulsating flow of gases to a substantially steady flow, thereby increasing the capacity and efficiency of the steam boiler.

Other objects of my invention will appear from the specification and will be particularly pointed out in the claims.

My invention will best be understood by reference to the accompanying drawings, in which I have illustrated two embodiments thereof, and in which Fig. 1 is a side view of 15 a Diesel engine of multiple cylinders and a steam boiler which is heated by the exhaust gases from the Diesel engines; Fig. 2 is a top view of the Diesel engine cylinders and the exhaust header therefor which are shown in 20 Fig. 1; Fig. 3 is a vertical section through a steam boiler and the associated parts for conducting the exhaust gases to and from the boiler; Fig. 4 is a view similar to Fig. 3, illustrating a modified form of boiler; Fig. 5 is a 25 sectional view on an enlarged scale illustrating the passages for conducting exhaust gases to and from the boiler, and the valves controlling the same, and Fig. 6 is a sectional view taken on the line 6—6 of Fig. 5.

Like reference characters indicate like parts throughout the drawings.

Referring now to the drawings, and first to the embodiments illustrated in Figs. 1 to 3, inclusive, 5, and 10 represents a plurality 35 of internal combustion engine cylinders illustrated as six in number, and 11 illustrates exhaust connections leading from the respective cylinders to a common exhaust pipe or header 12.

Referring to Fig. 3, 13 illustrates a steam boiler, generally, which is offset from the exhaust pipe 12 and the parts hereinafter referred to which are associated therewith. The boiler is preferably arranged vertically, and 45 is provided with a plurality of tubes 14, the upper and lower ends of which are secured to tube sheets 16 and 17. The outer shell of the boiler is indicated at 19, and the inner shell at 20. A cylindrical space 21 is thus 50 formed within the inner shell of the boiler,

and which is preferably filled with pieces of divided material 22 which extend down into a chamber 23 having a cylindrical wall 24 and a lower conical wall 25 forming a hopper. The pieces of divided material may be formed 55 of broken refractory material, preferably of substantially uniform size, or may be formed of balls of clay or metal or any other suitable material which is interposed in the path of the flow of gases between the exhaust from 60 the internal combustion engines and the heating surface of the boiler and leaving voids between the pieces for the gas flow.

The exhaust pipe is preferably turned upwardly as at 26, as best shown in Fig. 1, and communicates by a passage 27 leading to the space or chamber 21 in which the pieces of divided material are located. After passing through the voids or spaces between the pieces of divided material, the gases flow upwardly through tubes 14 into a chamber 28 70 from which a passage 29 leads to the outlet pipe or flue 30, which is preferably a continuation of the exhaust pipe from said engine. 75

Preferably, an oil burner 31 is also provided at the upper end of an upward extension 32 above the boiler, and which provides an enlarged combustion space 34 beneath the burner. From the combustion space 34, the gases 80 also flow downwardly between the pieces of divided material 22, and upwardly through the fire tubes as do the Diesel engine exhaust gases.

The refractory material 36 surrounding the 85 combustion space 34 is preferably provided with a casing 37. The inner casing 38 for the chamber 28 extends over the lower conical portion of the refractory wall for the combustion space and may be merged with the 90 casing 37, as illustrated in Fig. 3.

Referring particularly to Figs. 5 and 6, 39 and 40 are valve members pivoted at 41 and 42, respectively, and control the flow of gases from the exhaust pipe leading from the internal combustion engine or engines to the boiler, and from the boiler to the outlet flue, respectively. Preferably, the valve members 39 and 40 are in the form of plates as illustrated, the outer edges of the valves resting 100

against seats 43 and 44 in the valve casing, so that any foul matter, such as oil, carried over by the gases will be scraped from the edges of the valve members during the closing or opening operation. The valve members may be operated by handles 45 as illustrated in Fig. 6.

10 A chute 46 preferably passes through the upper portion of the wall surrounding the combustion chamber 34, and through which the granular material may be introduced into the combustion chamber, and from which it passes into the space 21 below. The chute 46 is preferably provided with a hopper 47 and with a rotary valve member 48 which permits the pieces of divided material to fall through the chute by gravity.

20 A chute 49, similar to the chute 46 (except for the hopper), is also provided at the lower end of the hopper 25 through which the pieces of divided material may be withdrawn. A drain pipe 50 is preferably provided in the lower portion of the hopper 25 through which any liquid, water or oil which may accumulate in the body of the hopper can be drawn off.

30 Preferably, a cover plate 51 is provided in conjunction with the top of the extension 32 in which the oil burner is mounted, so that when the oil burner is not in operation, it may be withdrawn and the cover seated against the top of the extension member 32 and form a sealed joint therewith, thereby preventing the escape of gases when the boiler 35 is operated by the exhaust gases from the internal combustion engine, and also preventing noise in the engine room.

40 The gases from an internal combustion engine, and particularly a Diesel engine, is sue in the form of a puffy or pulsating flow. Such a pulsating flow, however, passing over boiler heating surface is much less efficient, and a boiler heated with gases of this character has less capacity than one which is heated by the same amount of gases having a steady or substantially steady flow. By providing the pieces of material 22 which are interposed between the exhaust from the engine or engines and the heating surface of 50 the boiler, the gases are distributed while passing through the spaces between the pieces of divided material, and the pulsating flow is converted into a steady or substantially steady flow of gases, thereby increasing both the efficiency and capacity of the boiler.

60 The balls or pieces of divided material not only create an even flow of gases, but they catch the oil, gum, and soot carried over by the exhaust gases from the internal combustion engine. It will be understood that in practice, a certain amount of unconsumed fuel oil may sometimes be carried over with the products of combustion, and some lubricating oil is always carried over, and these materials are intercepted by the balls or

pieces of divided material, thereby preventing or minimizing their accumulation on the boiler heating surface, in the tubes in the embodiment illustrated.

70 The pieces of material 22 may readily be cleansed by withdrawing them through the chute 49 and burning or otherwise removing the foreign matter that has accumulated thereon, and they may then be again introduced to the chamber 21 through the chute 75 46. Under some conditions, it may be desirable to remove or partially remove the deposit from the material 22 by blowing gases through the chamber 21.

80 The construction of the boiler and associated parts illustrated in Fig. 4 is similar to that shown in Fig. 3, with the exception that the boiler is cylindrical in form and is surrounded by an annular space in which the pieces of divided material are received. The 85 same reference characters are applied in Fig. 4 to the same parts as those illustrated in Fig. 3, and the same reference characters, with small *a* appended, are applied to parts in Fig. 4 which are similar to those in Fig. 3. 90

The operation of the device embodying my invention will be readily be understood from the foregoing description, and is as follows:

95 When it is desired to heat the boiler by exhaust gases from the internal combustion chamber alone, the oil burner 31 is removed and the cover 51 is seated against the top of the extension 32. Both of the valves 39 and 40 are moved to their open position as 100 illustrated in Figs. 3 and 4, and the gases then pass from the exhaust pipe 12 through the passage 27, through the spaces between the pieces of divided material 22 into the chamber 23 from which they pass upwardly 105 through the tubes 14 into the chamber 28, and through the passage 29 to the outlet flue 30. The gases passing between the pieces of 110 divided material are converted from a pulsating flow to a steady or substantially steady flow, thereby increasing the efficiency and capacity of the boiler. At the same time, the pieces of divided material catch all or a major portion of the foreign material, such as oil or soot, which are carried over by the exhaust gases, and prevents their being carried to the heating surface of the boiler. The noise of the exhaust due to its pulsations is reduced by the same means that makes the flow steady.

115 By offsetting the boiler with relation to the exhaust pipe and the parts associated therewith, including the valves and outlet flue, repairs are readily made, and space, which is always an important consideration on vessels for which the equipment herein disclosed is particularly intended, is economized.

120 It will, of course, be understood that by opening the valves 39 to 40 in the positions shown in Figs. 3 and 4, either or both of the 125 exhaust gases and the oil burner may be uti-

lized for heating the boiler, and by changing the positions of the valves, the proportions of heating gases from the two sources may be varied as desired.

5 When it is desired to make repairs on the boiler, the valves 39 and 40 are closed as indicated in Fig. 5, and the exhaust gases from the internal combustion engine or engines are entirely short circuited around the boiler 10 and the boiler may be bodily removed if desired without interfering with the engine operation.

I claim:

1. In combination, a source of heated gases having a pulsating flow and carrying impurities, a steam boiler of the fire tube type comprising outer and inner shells and end tube sheets connecting the same, fire tubes connecting said tube sheets, a mass of finely divided pieces of material located within said inner shell, a conduit comprising an inlet to the boiler for conducting the gases from said source through said material and then through the fire tubes, and an outlet through 25 which the gases flow from said fire tubes, the steam boiler being offset from said inlet and said outlet.

2. In combination, a source of heated gases having a pulsating flow and carrying impurities, a steam boiler of the fire tube type comprising outer and inner shells and end tube sheets connecting the same, fire tubes connecting said tube sheets, a mass of finely divided pieces of material located within said inner shell and means for conducting the gases from said source through said material and thence through said fire tubes, and an outlet through which the gases may flow from said fire tubes, the inlet and the outlet 40 for the gases to and from said boiler being located at the same end of the boiler, the boiler being offset from said inlet and said outlet.

3. In combination, a source of heated gases having a pulsating flow and carrying impurities, a steam boiler of the fire tube type comprising outer and inner spaced shells and end tube sheets connecting the same, fire tubes connecting said tube sheets, a mass of finely divided pieces of material located within said inner shell, means for conducting the gases from said source through said material and thence through the fire tubes, an outlet through which the gases flow from said fire tubes, the inlet and the outlet for the gases to and from said boiler being located at the same end of the boiler and in substantial alignment, and valve means associated with said inlet and said outlet for bypassing the 55 gases around said boiler.

4. In combination, a source of heated gases having a pulsating flow and carrying impurities, a steam boiler of the fire tube type comprising outer and inner shells and end tube sheets connecting the same, fire tubes

connecting said tube sheets, a mass of finely divided pieces of material located within said inner shell, a conduit comprising an inlet for conducting the gases from said source through said material and thence through 70 said fire tubes, an outlet through which the gases flow from said fire tubes, the inlet and the outlet for the gases to and from said boiler being located at the same end thereof, an oil fired furnace located at the same end 75 of the boiler as said inlet and said outlet, and means for conducting the gases from said oil fired furnace through said mass of finely divided pieces of material and over the heating surface of said boiler in the same path as the gases from said source.

5. In combination, a source of heated gases having a pulsating flow and carrying impurities, a steam boiler, a conduit for conducting gases from said source to said boiler, 85 an outlet for the gases from said boiler located at the same end thereof as said inlet, said boiler being offset from said conduit and said outlet, a mass of finely divided pieces 90 of material being interposed in the path of the gases between said source and said boiler and bounded by the heating surface thereof and an oil fired furnace located at the same end of the boiler as said outlet, the gases from 95 said furnace flowing in the same path over said boiler heating surface as the gases from said conduit.

6. In combination, a source of heated gases having a pulsating flow and carrying impurities, a steam boiler of the fire tube type comprising outer and inner shells connected by end tube sheets, fire tubes connecting said tube sheets, a mass of finely divided pieces of material located within said inner shell and a conduit for conducting the gases from said source through said pieces of material and thence through said fire tubes, an outlet through which the gases flow from said fire tubes, the steam boiler being offset from said outlet, and an oil fired furnace located at the same end of the boiler as the discharge end of 100 said conduit and said outlet, the gases from said furnace flowing in the same path over said boiler heating surface as the gases from said source.

7. In combination, a source of heated gases having a pulsating flow and carrying impurities, a steam boiler of the fire tube type comprising outer and inner shells defining two 120 spaces, end tube sheets closing one of said spaces and forming a water chamber, fire tubes connected to said tube sheets and passing through said water chamber, the other space forming a passage for the gases, a mass of finely divided pieces of material located within the space forming a pass for the gases, the gases flowing through said mass of finely divided material and in a return pass through 125 said tubes, and means whereby impurities in 130

said mass of finely divided material may be withdrawn.

8. In combination, a source of heated gases having a pulsating flow and carrying impurities, a steam boiler of the fire tube type comprising outer and inner shells and end tube sheets connecting the same, fire tubes connecting said tube sheets, a mass of finely divided pieces of material located within said inner shell, a conduit comprising an inlet to the boiler for conducting gases from said source through said material and then through the fire tubes, an outlet through which the gases flow from said fire tubes, and means whereby impurities in said mass of finely divided material may be withdrawn.

9. In combination, a source of heated gases having a pulsating flow and carrying impurities, a steam boiler of the fire tube type comprising outer and inner shells and end tube sheets connecting the same, fire tubes connecting said tube sheets, a mass of finely divided pieces of material located within said inner shell, a conduit comprising an inlet to the boiler for conducting gases from said source through said material and then through the fire tubes, an outlet through which the gases flow from said fire tubes, a hopper located beneath said inner and outer shells and in which at least a portion of said pieces of material are located and means whereby impurities in said mass of finely divided material may be withdrawn from said hopper.

10. In combination with a source of heated gases having a pulsating flow and carrying impurities; a steam boiler comprising inner and outer shells, a mass of pieces of heat resisting bodies positioned within the inner shell, means for conducting the heated gases to the inner shell so that they pass between said bodies and deposit their impurities thereon, means for maintaining water between the shells, and means for conducting the gases from the inner shell through the space between the shells so that they cause steam to be generated as they pass through that space.

11. In combination with a source of heated gases having a pulsating flow and carrying impurities; a steam boiler installation comprising, a shell affording a passage for the gases, a mass of separate solids filling a part of the shell with the solids spaced sufficiently to permit the passage of gases through the shell, means for directing the gases through the shell so that their flow substantially loses its pulsating characteristic, a steam generator section embracing the shell, and means for directing the gases into contact with the generator section after they have passed through said mass of solids.

12. In combination, a source of heated gases having a pulsating flow and carrying impurities, a steam boiler including an outer shell and having fire tubes within the shell,

means located within the shell acting as a filter to remove impurities from the gases before they pass through the fire tubes, a conduit comprising an inlet to the shell for conducting the gases from said source through said filter and then through the fire tubes, an outlet through which the gases flow from said fire tubes, and an exhaust line leading from said source past the shell at one side thereof and connected successively to the inlet and outlet at closely adjacent positions, the steam boiler being offset from said inlet and said outlet.

CHARLES E. LUCKE.
